UNITED STATES PATENT OFFICE.

ALBERT SCHWANZ, OF ST. LOUIS, MISSOURI.

PUNCH-CENTERING MACHINE.

Application filed February 9, 1925. Serial No. 8,035.

To all whom it may concern:

Be it known that ALBERT SCHWANZ, a citizen of the Republic of Germany, residing at St. Louis, State of Missouri, has invented 5 certain new and useful Improvements in Punch-Centering Machines, of which the following is a specification.

The object of my device is to make a punch centering machine to be used particularly for locating exact centers for varying machine operations. A further object is to make a device that will exactly locate and punch the center of rods and bars of cross sections of different geometrical shapes. A 15 further object of my device is to devise a machine for the locating and drawing of lines that are parallel to each other and lines that are perpendicular to each other, and locating punch centers on these lines at varying predetermined distances from each other and from a definite starting point. A still further object is to devise a machine having in combination a T square and a punch in combination with graduated edges to accomplish efficiently the objects stated. A still further object is to devise a machine that is made of few and simple parts that lend themselves readily to multiple production, that may be easily assembled and taken 25 apart, and that can be for these reasons cheaply and efficiently made.

With these and other objects in view, my invention has relation to certain novel features of construction and arrangement of parts as will be hereinafter more fully described, pointed out in the claims, and illustrated in the drawings in which,

Fig. 1 is a plan view of my device, and

Fig. 2 is a side elevation of my device, and

40 Fig. 3 is a sectional elevation on the line 3-3 of Fig. 2, and

Fig. 4 is a sectional elevation on the line 4-4 of Fig. 2, and

45 Fig. 5 is a sectional elevation on the line 5-5 of Fig. 2, and

Fig. 6 is an inverted fragmental plan of my device when used for locating centers on cylindrical cross sections, and

50 Fig. 7 is an inverted plan of my device when used for locating centers of rods or bars of non-circular sections.

Fig. 8 is a sectional elevation on the line 8-8 of Fig. 7, showing the means for selectively detachably securing a graduated scale 55 to my device.

Fig. 9 is a sectional elevation of the punch

guide 40 and the stud 34, together with their joining means and a fragmental elevation of the U shaped member 28. Fig. 10 is a fragmental end elevation of my device. 60

Numeral 9 designates a T square having the T section member 10 and slotted member 11 formed integral at right angles to the T section member 10.

Numeral 12 designates a handle formed 65 integrally with the T section member 10 at its center. At the jointure between the handle 12 and the T section member 10, beneath the slotted member 11 is formed the rectangular cavity 13. The slot of the slotted 70 member 11 extends to the top of the rectangular cavity 13. The slot 14 of the slotted member 11 extends longitudinally almost to the outer end of the slotted member 11, as is clearly shown in Fig. 1. The handle 75 12 is so positioned that a central line passing through the slot 14 will pass through the center of the handle 12. A groove 15 or graduation is marked on the top in the center of the handle 12. This groove 15 is continued to the left in Fig. 1 to the right end of the slot 14 in Fig. 1. Near the end of one of the arms of T square 9 is integrally formed the arm 16, to which is secured the post 17. The post 17 consists of the threaded 80 rod 18 passing through a hole 19 near the end of the arm 16. The winged nut 20 is in threaded engagement with the end of the threaded rod 18 below the hole 19. By means of the threaded rod 18 and the 90 winged nut 20, the post 17 may be firmly secured to the arm 16. In order to secure the extension member 21 to the post 17, a hole slightly larger than the extension member 21 is formed near the top of the post 17. 95 Into this hole the extension member 21 may be inserted. In order to secure the extension member 21 in any particular position, the set screw 22 is provided, which is in threaded engagement in a hole at the top of the post 17, and extends to the hole in the post 17. In order to prevent the extension member 21 from turning when in position in the post 17, one face of it may be flattened.

To the free end of the extension member 105 21 is secured the finger 23, which is secured to the extension member 21 by virtue of having a cup formed in its inner end into which the end of the extension member 21 may be positioned. A set screw 24 is in threaded 110 engagement in a hole in the finger 23, and of such length as to come in contact with the

end of the extension member 21. To the end of the finger 23 is integrally secured the marking rod 25. At right angles thereto in the loop 26, formed in the finger 23 is secured a conventional lead pencil 27. Mounted on the slotted member 11 and the T section member 10 is the U shaped member 28, which is secured to the T section member 10 by means of the studs 29 formed on the T section member 10 and the nuts 30 in threaded engagement on the ends of the studs and over the U shaped member 28. The studs 29 pass through holes in the U shaped member 28. The opposite end of the U shaped member 28 is secured to the slotted member 11 by means of a stud 30a. The stud 30 is secured to the slotted member 11, passing through the end of the slot in the U shaped member 28, and through the washer 31. The washer is of a diameter larger than the width of the slot in the U shaped member 28. A pin 32 passes through a hole in the top of the stud 30a. Each arm of the U shaped member 28 has an L section.

Numeral 33 designates a plate slidably secured between the slotted member 11 and the U shaped member 28. This plate may be moved the entire length of the slot in the slotted member 11. A stud 34 is mounted in the center of the plate 33 and extends through the slot 14 and through the slot of the U shaped member 28. The upper end of the stud 34 is threaded. A plate 35 having a hole in its center is positioned on the U shaped member 28 over the stud 34. On the under surface of the plate 35 a projection 36 is formed of a width slightly less than the width of the slot in the U shaped member 28, so that the plate 35 may be slid in the slot of the U shaped member 28. The projection 36 acts as a guide for this sliding operation.

Numeral 37 designates a nut in threaded engagement on the stud 34. By tightening the nut 37 against the plate 35, the plate 33 is brought upwardly against the lower surface of the slot of the U shaped member 28. By this means the plate 33 may be secured in any position. The plate 33 has an integral upward extension 38 formed at right angles therewith and extending through the slot in the U shaped member 28. To this extension 38 by means of the screws 39, the punch guide 40 is fastened. A longitudinal hole 41 passes through the punch guide 40. Numeral 42 designates the punch having a point 43 and the shaft 44. Numeral 45 designates a sleeve in sliding engagement on the shaft 44 of the punch 42. Numeral 46 designates a coiled spring positioned over the shaft 44 of the punch 42, above the punch guide 40 and below the sleeve 45. Numeral 47 designates a slotted finger secured to the sleeve 45 by means of the screw 48. The slotted finger 47 extends in

a state of parallelism with the punch 42 and downwardly. A stud 49 is formed on the punch guide 40 and the shaft of the stud passes through the slot in the slotted finger 47. When the slotted finger 47 and the stud 49 are in the position just indicated, a nut is placed in threaded engagement on the stud over the slotted finger 47. The purpose of the slotted finger 47 is to prevent the punch 42 from becoming disengaged or falling out of the punch guide 40. The slot in the slotted finger 47 is of such length that when the stud 49 is at the bottom of the slot of the slotted finger 47, the point 43 of the punch 42 will not protrude beyond the lower end of the longitudinal hole 41 in the punch guide 40. The purpose of the coiled spring 46 is to return the punch 42 to the position just indicated, after the spring has been compressed and the punch lowered so that the point 43 of the punch 42 extends beyond the lower surface of the punch guide 40, that is out of the longitudinal hole 41 of the punch guide 40.

For purposes to be described in the operation of my device I have provided a graduated ruler or scale 50, which is positioned on the one lateral face of the U shaped member 28.

On the side of the punch guide 40 adjacent the rule 50 is secured the pointed finger 52. The point of the pointed finger 52 when the punch guide 40 is moved longitudinally in the U shaped member 28 moves directly over the graduated scale or ruler 50. This point is in the same vertical plane as the point of the punch 42. The exact distance that the center of the punch is positioned from the zero on the rule 50, which is at the right end in the figures in the drawing may be easily determined by reading the graduation on the scale or rule 50 immediately beneath the point of the pointed finger 52. In order to punch a center at a certain distance from the edge of an object, it is only necessary to place my device so that the center of the punch 42 is at the desired position, tighten the nut 37 and strike the top of the punch 42 a blow with the palm of the hand. This will move the punch and make the mark at the desired place. The spring will return the punch to its normal position. In order to locate the center of bars having a square cross section, it is necessary to employ an additional scale 54 which has a stud 55 formed thereon near its one end and which is cut at an angle of 45 degrees at the other end, and having the projection 57 formed thereon. Near the end of the T section member 10 on its lower side is formed the hole 58. The scale 54 is of such length that when the stud 55 is inserted in the hole 58, the point of its opposite end will protrude to the absolute corner of the rectangular cavity 13.

In locating the center of a bar having a square cross section, it is only necessary to position the bar in my device so that its end will be in contact with the scale 54 when 5 in position, and its one edge positioned in the rectangular cavity 13, as shown in Fig. 7. The length of the diagonal of the square cross section may be directly read on the scale 54, this distance is divided by two and 10 the point of the pointed finger 52 placed above the graduation on the rule 50 representing that distance. The nut 37 is then tightened, the scale 54 removed, and the punch 42 given the blow with the hand 15 necessary to operate it, as previously described. A punch hole will then be made in the exact center of the square section of the rod.

When it is desired to obtain the center of 20 a circular bar section, the scale 54 is placed in position and the end of the bar of circular section is placed as shown in Fig. 6 with its face against the rule 54 and its sides in contact as far as possible in the rectangular 25 cavity 13. It will be seen that since the scale 54 has its zero graduation at the apex of the rectangular cavity 13, and that since the surface now to be measured does not come to that point, that the center of the 30 circular section could not be obtained by dividing the distance by two, as was done in the case of the square section. In order to find the center, therefore, it becomes necessary to read the distance on the scale 54 35 to the outer periphery of the circular rod, and then to subtract the distance between the other and opposite surface of the rod and the zero on the scale 54, and then dividing this distance by two. This radial 40 distance may then be located on the rule 50 in the same manner that it was previously located.

A vertical graduation 15' is positioned in 45 the center of the rear face of the punch guide 40. In order to punch a series of holes in a line perpendicular to another line or surface, it is only necessary to position my device as a T square against the edge and to sight along the graduation 15 on the 50 handle 12 and on the punch guide 40. These lines are in the same vertical plane with the point 43 of the punch 42. These punch marks on this line may be located a predetermined distance from any desired line and 55 a predetermined distance between each other by the use of the rule 50.

Another example of the use of my device is for the following work. Assume we have 60 a rectangular bar of metal two feet in length and three inches wide and of any thickness. It is desired that holes be drilled four inches apart and in the center of the width. By means of the rule 50 set the point 65 43 to the graduation reading one and one-half inches, that is to say, one-half of the

width of the bar, then with a rule measure a distance of four inches from the left end of the bar and with the straight edge of the T section of my device draw a line perpendicular to the longitudinal face of the bar, and 70 therefore parallel to the left end of the bar, then place my device so that the vertical graduation of the punch guide 40 is directly over the line, then operate the punch as indicated, or by striking it with a hammer. 75 The punch mark made will be exactly four inches from the left end of the bar and midway between the sides of the bar. In order to make the second punch mark on the same line, but four inches to the right of the first 80 punch mark, proceed as before. This process may be continued for each of the punch marks. In order to obviate the necessity of measuring the four inch distance between each subsequent punch mark, after the second center punch hole is made, the following method and parts of my device are used. The center punch 42 is held manually in the second hole by adjusting the extension member 21, the point of the marking rod 25, or 85 of the lead pencil 27 may be placed in the first punch mark. When this is accomplished, the extension member 21 is secured in its position by the method previously described. The distance between the point 43 of the punch 42 and the point of the marking rod 25 will now be exactly four inches. In order to make the subsequent center 90 punch marks when the device is in the adjusted position just indicated, the device need only be moved to the right so that the point of the marking rod 25 will be in the second hole and the T square positioned. By striking the center punch 42 the third center 100 punch mark will be made. This may be continued for each subsequent marking. This latter method can, of course, not be used for distances greater than permitted by the length of the extension member 21, nor for distances less than half the width of the 105 U shaped member 28.

When the distance between the punch marks varies, the extension member 21 cannot be used. In that event, the former method described must be continued. 110

What I claim and mean to secure by Letters Patent is,

1. In combination with a T square, a punch guide slidably secured thereon, a punch slidably secured in said punch guide, a sleeve secured to said punch, a slotted arm secured to said sleeve, a stud secured to said punch guide in sliding engagement in the slot of said slotted arm, a spring positioned on said punch between said sleeve and said punch guide. 120

2. In combination with a T square, a punch, a punch guide and a pointed finger, said punch operatively secured in said punch guide, said punch guide in sliding en- 130

gagement on said T square, a scale secured to said T square adjacent said pointed finger, the latter being secured to said punch guide.

5. In combination with a T square, having a handle secured thereto, said handle having a graduation centrally disposed thereon, a punch guide having a vertical

centrally disposed graduation formed thereon, said punch guide slidably secured to said T square, a punch secured in said punch guide, a pointed finger secured to said punch guide, a scale secured to said T square, adjacent said pointed finger.

In testimony whereof I affix my signature.

ALBERT SCHWANZ.
